(57) **CLAIM**

I claim the ornamental design for a massage tool, substantially as shown and described.

DESCRIPTION

FIG. 1 is a top plan view of a massage tool showing my new design, the bottom plan view is a mirror image;

FIG. 2 is a side elevational view of the massage tool shown in FIG. 1 taken along line 2—2 and looking radially inward;

FIG. 3 is a side elevational view of the massage tool shown in FIG. 1 taken along line 3—3 and looking radially inward;

FIG. 4 is a side elevational view of the massage tool shown in FIG. 1 taken along line 4—4 and looking radially inward; and,

FIG. 5 is a perspective view of the massage tool shown in FIG. 1.
